VERNIER CALIPER RADII ATTACHMENT

George Podolan, Detroit, Mich.

Application October 25, 1944, Serial No. 560,269

2 Claims. (Cl. 33—159)

1 My invention relates to a new and useful improvement in a vernier caliper, and more particularly to an attachment for converting the caliper to a divider. It is an object of the present invention to provide a caliper of the vernier type with an attachment that can be readily attached or detached to the tongs or prongs of the caliper in a manner which will permit reading the same scale on the caliper.

It is another object of the present invention to provide an attachment which can be fixedly secured to the tongs or prongs of the caliper for converting the same into a rigid beam compass scribe or divider.

It is another object of the present invention to provide a device of this class which will be simple in structure, economical of manufacture, rigid in construction and highly efficient in use.

Other objects will appear hereinafter.

It is recognized that various changes and modifications may be made in the detail of structure illustrated without departing from the invention itself, and it is intended that such variations and changes shall be encompassed within the scope of the claims which form a part of this specification.

Forming a part of this specification are drawings in which,

Fig. 1 is a plan view of the caliper with the invention attached;

Fig. 2 is a cross-sectional view taken on line 2—2 of Fig. 1;

Fig. 3 is a fragmentary cross-sectional view taken on line 3—3 of Fig. 2;

Fig. 4 is a cross-sectional view of a modified form of the invention.

Referring to the drawings, there is shown a bar 10 having a tongue or prong 11 formed integral therewith and extending at right angles thereto. The bar 10 is provided with a scale 12. Slidably mounted on the bar 10 is a vernier slide 13 having a tongue 16 which extends in alignment and parallel with the tongue 11. The slide 13 is provided with an opening 14 for reading the scale 12. Markings 15 are provided on the slide 13 for cooperative reading with the scale 12. An anchor slide 20 is slidably mounted on the bar 10 and is tied to the slide 13 by means of a threaded stud 17 which is anchored on the block 13 and projects through the anchor slide 20. A nut 21 is carried by the anchor slide 20 and is threaded on the stud 17. The bar 13 and slide 20 may be secured stationary on the bar 10 by set screws 18 and 22 respectively. The

tongues 11 and 16 are each provided with facings 25. In normal use, the caliper is read with the object that is to be scaled placed between the tongues 11 and 16 against their faces 25.

2 Each of the tongues 11 and 16 is formed alike so that a description of one, it is believed, will suffice for both. The face of the prong, opposite the face 25, is cut away to provide the arcuate face 27 and the planar face 28. A marker 40 is placed against a face 25 and held thereto by a band 34 which also encircles the tongue. Secured by pin 33 in the band 34 is a block 30, a face of which is formed in an arcuate section 41 for engagement with the arcuate portion 27.

10 Formed on the block 30 is a projection 31 for engagement with the face 28. A projection 32 is formed on the block 30 and adapted to engage one face of the prong 16. A spring 38 is disposed in a bore 37 formed in the block 30, one end of

15 20 which engages the pin 33 and its opposite end engages the bore 37 for moving the block 30 against the thickened end 35 of the band 34. A set screw 36 is threaded through the thickened portion 35 of the band 34 for engagement against a block 30.

25 It will be noted that by the present arrangement of parts, the caliper can be quickly and easily converted for use as a divider or beam compass scribe by merely loosening screw 36 and removing the marker and band. Likewise, its attachment is easily and quickly made by fastening of screw 36. The block 30 is at all times carried by the band 34 so as to facilitate its attachment to the caliper. A slot 41 is formed in the block 30 to permit movement of the block about the pin

30 33. In attaching the device, the user can, by merely holding in one end the marker and band, slide the assembly onto the end of the prong. The block 30 will be, by action of the spring 38, moved outwardly against the end of the band and

35 40 away from the steps 27 and 28 until the assembly has been fully slid on the prong, whereupon the tightening of the screw 36 will move the block against the tension of the spring 38 to engage the steps and frictionally lock the assembly upon the prong. By the use of the faces 27 and 28, the assembly cannot creep on the prongs, thereby permitting the user to apply pressure upon the caliper without fear that the markers 25 will slide when it is used as a beam compass scribe

45 50 or as a divider against an object that is to be measured or scribed. It will be noted that, if desired, the calipers can also be used for obtaining inside measurements by the use of the present attachment.

55 To further facilitate manufacture, the lower

step 28, if desired, may be radiused as shown in Fig. 4 to engage a V-groove formed in the lower step of the section 31 in the block 30. This arrangement permits an easier alignment of the parts.

What I claims as new is:

1. In a caliper of the class described, an elongated bar; a prong carried by and projecting outwardly from one edge of said bar; a marking instrument engaging one face of said prong and projecting beyond said prong and the opposite face of said prong being cut away to provide planar faces meeting an arcuate face; a band encircling said prong and said marking instrument for clamping said marking instrument against the prong; a block positioned within said band and having a slot formed therethrough connecting with a passage extended at substantially right angles to said slot; a pin projected through said band and through said slot for securing said block on said band, said pin being of less diameter than the width of said slot, said block having an arcuate face and planar faces for engaging corresponding faces on said prong; and a spring positioned in said passage and engaging at one end with said pin and at the opposite end with said block for normally urging said block in one direction relatively to and against one side of said band.

2. In a caliper of the class described, an elongated bar; a prong carried by and projecting outwardly from one side of said bar; a marking instrument engaging one face of said prong and projecting beyond the end of said prong, the face of said prong opposite said engaged face being cut away to provide planar faces meeting

5 with an arcuate face; a band encircling said prong and said marking instrument for binding the same together; a block positioned within said band and lying between one side thereof and said prong, said block having an arcuate face and planar faces for engaging corresponding faces on said prong, said block having a passage formed therein and provided with a slot formed therethrough at right angles to said passage; a pin 10 projected through said band and said slot, said pin being of less diameter than the width of said slot for permitting movement of said block on said pin relatively to said band within the limits of said slot; and a spring positioned in said passage and engaging at one end with said block and at the opposite end with said pin for normally resisting movement of said block on said pin in one direction.
